UNITED STATES PATENT OFFICE

116,995

DESIGN FOR AN EARTH ANCHOR

Albert B. Chance, Centralia, Mo.

Application December 8, 1938, Serial No. 81,655

Term of patent 14 years

To all whom it may concern:

Be it known that I, Albert B. Chance, a citizen of the United States, residing at Centralia, in the county of Boone and State of Missouri, have invented a new, original, and ornamental Design for Earth Anchors, of which the following is a specification, reference being had to the accompanying drawings forming part thereof.

Fig. 1 is a view in perspective of an earth anchor embodying the design;

Fig. 2 is a bottom plan view of the earth anchor;

Fig. 3 is a side elevational view of the earth anchor;

Fig. 4 is a sectional view, taken on a vertical plane passing through the middle of the anchor, in the plane of the paper, in Fig. 3;

Fig. 5 is an end view of the anchor, taken from the right end of Fig. 3; and

Fig. 6 is an end view of the anchor, taken from the left end of Fig. 3.

I claim:

The ornamental design for an earth anchor, as shown.

ALBERT B. CHANCE.
